United States Patent Office

Des. 229,070
Patented Nov. 6, 1973

229,070

COMBINATION RADIO AND TAPE PLAYER

George E. Lyall, Melrose, Mass., assignor to Automatic
Radio Mfg. Co., Inc., Melrose, Mass.

Filed Oct. 12, 1972, Ser. No. 297,053

Term of patent 14 years

Int. Cl. D14—01, 03
U.S. Cl. D26—14 B

Fig. 3.

Fig. 4.

FIG. 1 is a perspective view of a combination radio and tape player showing my new design;

FIG. 2 is a side view thereof;

FIG. 3 is a bottom plan view thereof; and

FIG. 4 is a rear view thereof.

I claim:

The ornamental design for a combination radio and tape player, substantially as shown and described.
